UNITED STATES PATENT OFFICE.

ELMER S. OLMSTED, OF LOUISVILLE, KENTUCKY, ASSIGNEE TO CHEATHAM ELECTRIC SWITCHING DEVICE CO., INC., OF LOUISVILLE, KENTUCKY, A CORPORATION OF KENTUCKY.

ELECTRICALLY OPERATED AND CONTROLLED RAILWAY SWITCHING DEVICE.

Application filed April 28, 1924, Serial No. 709,426. Renewed August 31, 1928.

This invention relates to electrically operated and controlled railway switches, being an improvement upon the devices and apparatus claimed in my United States Patents Nos. 978,053 and 1,079,991. In my said patents, I showed and described and claimed apparatus for controlling the track-switch operation so that where several cars in a train are operated by one motorman, or 10 where single cars follow each other closely, there will be no danger of having some of the wheels of the train switched in one direction and some in another; or of the track-switch being moved between wheels of a preceding car.

The object of my present invention is to provide a more efficient and more reliable electrically operated and controlled switching device for railways. A new feature for 20 insuring reliable and positive action resides in the fact that I provide means for holding a solenoid and a portion of the circuits involved, normally energized, by which feature I obtain the very desirable result that even 25 in the event of power leaving the system, the switch operating mechanism will automatically be left open circuited and inoperative.

For a more particular description of my invention, reference is to be had to the drawing herewith in which Figure 1 is a diagrammatic view of a preferred employment of 30 my invention.

In Fig. 1, I have shown not only the controlling device, but the trolley-wire and the 35 important parts of the control and switch throwing device such as commercially used for this purpose. An electric car approaching the switch which is to be thrown by means of solenoid GM, passes trolley contactor A', in which the trolley-wheel bridges the two contactor strips A and A¹, and establishes a circuit from trolley-wire E with 40 wires F, solenoid KL, wire KL², contactor strip A, trolley-wheel, contactor strip A¹, wire KL¹, armature L⁷, contact points L⁵, wire GM², armature KL³, and either wires 45 GM³, or GM¹, (depending upon whether the car passes contactor using or not using motive power), solenoids GM^a or GM^b, thence 50 to ground.

In Figure 1, I have shown four contactors B, C, C¹ and C², all of which are of similar design, and are so arranged that the trolley-wheel sends current into them from the

trolley-wire without the wheel leaving said 55 wire. Contactors B and C only are ordinarily used, but C¹ and C² may be substituted for C, under certain operating conditions.

After the switch has been thrown by either 60 solenoid GM^a or GM^b, incident to the trolley-wheel bridging contactor strips A and A¹, the trolley-wheel advances until it sends current into relay M, from contactor B, which attracts the armature M² and opens a normally closed circuit connected therewith, and thereby causes the plunger of relay L to drop by gravity, by reason of the interruption of 65 said current which previously was flowing through following circuit: F, F¹, F², M², F³, 70 L⁶, L⁸, F⁴, resistor L¹ and solenoid L to ground. With the dropping of the plunger of solenoid L, the contacts at L³ and L⁵ are opened, and contacts at L⁴ closed.

Figure 1 shows L in normally energized 75 circuit position. By reason of Fig. 1 being diagrammatic, it is necessary in that diagram to show armature L⁶ by means of two solid lines and two dotted lines.

It will be noted that at this stage of the 80 operation, the coils GM^a and GM^b are open circuited, and therefore cannot be energized, by reasons of the contacts at L⁵ being open. Solenoid L is in circuit and therefore responsive to energization from either of the 85 C contactors, by reason of a circuit being established through the contacts at L⁴.

It will be noted that the controlling solenoid L in my controlling device is normally energized, in which condition it holds the 90 circuit ready for switch operation, and that when it is deenergized by reason of a trolley-wheel contacting controlling contactor B, the switch operating circuit is opened, and then held open, by gravity. This feature is of 95 very great value and has been long sought for in the industry for the purpose of providing an effective and protective control, even when power leaves the system, which has been pointed out supra.

The deenergizing contactor B is located 100 with reference to the various car-lengths in terms of the positioning of the switch operating contactor A, and unlocking contactor C, or C¹ and C². If a plurality of cars come into the block before the first one which has deenergized the system at contactor B, has reenergized the system at contactor C,

- or C¹ or C², the following cars will each find the switch operating circuit open at contacts L⁵, due to individual locking at contactor B; and the switch therefore inoperative. 5
5 The proper placing of contactor B will therefore cause each trolley-wheel to individually energize relay M, and render the switch inoperative against the action of any following trolley-wheel, in train or singly; and to 10 hold the track switch inoperative while a following trolley wheel is passing switch operating contactor A, and until the preceding trolley car has passed the switch, and a C contactor. 15
15 A great many combinations of this broad idea are possible and practical and I do not wish to limit myself to the specific arrangement shown herein or to any specific type of switch-throwing apparatus other than by 20 the scope of claims which I give herewith:
1. In an electrically operated railway switch throwing apparatus comprising contactors adjacent a trolley wire and ground magnets so connected as to operate a track 25 switch; all connected thru a plurality of separate circuits, with means for opening and closing said circuits; the first circuit of the protective equipment being a control for a second normally closed circuit, which in 30 turn controls a third circuit through which either of the two branches of the selective switch operating circuit are energized to operate the track switch to one or the other of its two positions; said first and second 35 circuits being so arranged and connected to separate contactors as to control the third circuit.
2. In an electrically operated railway switch throwing apparatus comprising contactors adjacent a trolley wire and ground magnets so connected as to operate a track switch; all connected thru a plurality of separate circuits, with means for opening and closing said circuits; the first circuit of 40 45 the protective equipment being a control for

a second normally closed circuit, which in turn controls a third circuit through which either of the two branches of the selective switch operating circuit is energized to operate the track switch to one or the other of 50 two positions; the first and second circuits being so arranged and connected to separate contactors as to control the third circuit to prevent or permit the operation of said switch throwing apparatus. 55

3. In an electrically operated railway switch throwing apparatus comprising contactors mounted adjacent to trolley wire and ground magnets so connected as to operate a track switch; all connected thru a plurality of 60 separate circuits each connected to a contactor adjacent the trolley wire with means for opening and closing said circuits; the first circuit of the protective equipment being a control for a normally closed second 65 circuit which in turn controls a third circuit through which either of the two branches of the selective switch operating circuit is energized to operate the track switch to one or the other of two positions; said first and 70 second circuits being so arranged and connected to separate contactors as to control the third circuit. 75

4. In an electrically operated railway switch throwing apparatus comprising contactors adjacent a trolley wire and ground magnets so connected as to operate a track switch; all connected thru a plurality of 80 separate circuits; the first circuit of the protective equipment being a control for a normally closed second circuit which in turn controls a third circuit through which either of the two branches of the second circuit is energized to operate the track switch to one or the other of the two positions; the remaining 85 circuits being so arranged and connected to separate contactors as to prevent the energization of one of the two circuits and permit the energization of the remaining circuit. 85
